UNITED STATES PATENT OFFICE

HIRAM BARBER, OF CHICAGO, ILLINOIS.

HEATING-STOVE.

SPECIFICATION forming part of Letters Patent No. 660,357, dated October 23, 1900.

Application filed January 9, 1899. Serial No. 701,652. (No model.)

To all whom it may concern:

Be it known that I, HIRAM BARBER, a citizen of the United States, residing at Chicago, in the county of Cook and State of Illinois, 5 have invented a new and useful Heating-Stove, of which the following is a specification.

My invention relates to improvements in heating-stoves in which a combined cross-partition and register is located above the grate, the object being to procure combustion of gases. An air-shaft is also provided to afford a safety-duct through the cross-partition to prevent the escape of coal-gas into 15 the room. I attain these objects by the mechanism illustrated in the accompanying drawings, in which—

Figure 1 is a sectional view of my device, showing the interior arrangement of the 20 cross-partition and register composed of the plates P and R, the air-shaft A, and grate G. Fig. 2 is a plan view of the register composed of the plates P and R when open—that is, with the openings o and o' coinciding—and 25 showing also the upper end of the air-shaft A. Fig. 3 is a plan view of the register when closed.

In the construction of my heating device it will be observed that I make use of the plates 30 P and R, which in combination form a cross-partition and register located above the grate G. The distance between the grate G and the cross-partition is sufficient to afford a suitable chamber for the combustion of fuel. The partition-plate P is provided with the openings o', which are preferably arranged in a semicircular form. Superincumbent upon the 35 partition-plate P is placed the register-plate R, which is also provided with the openings o, arranged in semicircular form to correspond with the openings o' in the partition-plate P. The register-plate R is also provided with the handle h, which operates in the slot S, provided in the casing K, and which slot is so 40 arranged as to permit rotary motion of the register-plate R and is of a sufficient width to permit the opening or closing of the openings o' in the partition-plate P by the register-plate R. The partition-plate P is located a 45 sufficient distance from the top of the stove to afford a secondary combustion-chamber above the partition-plate P for the complete

combustion of the gases arising from the fire below the cross-partition when the degree of heat is sufficient to ignite the same in their 55 passage through the openings o' and o.

A is an air-shaft which is tightly inserted into the opening O, provided therefor in the partition-plate P. The air-shaft A when in position extends downward from the cross-partition, preferably near the outer casing K, toward the grate G a distance sufficient to 60 secure an oblique or side draft from the fire on the grate G through the air-shaft A when the openings o' in the partition-plate P are 65 closed by the superincumbent register-plate R. The door d is provided for the introduction of fuel into the combustion-chamber between the cross-partition and the grate G. The door d' is provided for the removal of the 70 debris arising from the combustion of fuel upon the grate G.

When fuel is ignited upon the grate G and the openings o' and o are coincident, the gases arising from combustion ascend through the 75 passage formed by the openings o' and o and thence out through the pipe X. When, however, the apertures o' in the partition-plate P are closed by the register-plate R, the only exit for the gases arising from the combustion 80 of fuel upon the grate G is the air-shaft A. The air-shaft A is never closed, and there is always, to some extent, a flow of heated gases upward through the same. The line of draft to the same from the ignited fuel located upon 85 the grate G is, however, oblique and not as forceful as the direct-ascending draft through the passages formed by openings o' and o. The air-shaft A is of such size and capacity, proportioned to the size of the stove, as to afford a safety escape for the excessive accumulation of gases. The advantage of this arrangement as embodied in my device is two-fold. When the register is closed, the air-shaft always affords a safety exit for the accumulated coal-gas from the combustion-chamber below the partition. This arrangement obviates the danger usually incident to the escape of coal-gas and is a safeguard against carelessness in operating the register-plate R—a constant menace to the occupants 90 of rooms heated by stoves. When the register is closed, the ascending or direct upward draft from the fire is cut off, and the draft is 95 100

thereupon converted into an oblique or horizontal draft from the surface of the fire to the lower end of the air-shaft A and the lowest possible support given to the continued 5 combustion upon the grate G consistent with safety to the occupants of the room heated by the stove; or, in other words, when the register is closed the least possible amount of fuel is consumed upon the grate G consistent 10 with the safety of the occupants of the room heated by the stove. Economy and prudence are thus happily combined.

Having thus explained the mode of construction and the nature and object of my 15 invention, what I claim as novel, and for which I seek Letters Patent, is the following, to wit:

1. In a stove, the combination with the casing of a combined register and cross-partition 20 above the grate, a door in said casing below said cross-partition, means for opening and closing said register, and an air-shaft extending downward from said cross-partition and forming a safety-duct for the escape of excess-

sive accumulation of gases from the coal-com- 25 bustion chamber and adapted to moderate the combustion of fuel by inducing an indirect or oblique draft, substantially as described.

2. The combination with the casing K, of 30 the register formed of the plates P and R which are provided with the openings o and o', the handle h to operate said register, and the air-shaft A, substantially as and for the purpose described.

3. The combination with the casing K, of 35 the grate G, a cross-partition above the grate and formed of the plates P and R which are provided with the openings o and o' and adapted to be used as a register, the handle h to 40 operate said register and the air-shaft A, substantially as described.

Witness my hand this 6th day of January,
A. D. 1899.

HIRAM BARBER.
